UNITED STATES PATENT OFFICE.

CARL J. WATROUS, OF MARION, OHIO.

FOOT-SUPPORTER.

1,187,578.

Specification of Letters Patent. Patented June 20, 1916.

Application filed October 11, 1915. Serial No. 55,251.

To all whom it may concern:

Be it known that I, CARL J. WATROUS, a citizen of the United States, residing at Marion, in the county of Marion and State of Ohio, have invented certain new and useful Improvements in Foot-Supporters, of which the following is a specification, reference being had to the accompanying drawings.

10 This invention relates to certain improvements in foot supports, and it is an object of the invention to provide a device of this general character insertible within a shoe and having novel and improved means whereby an even wearing of the shoe results from the use thereof.

With a weak or crooked ankle bone, even when so slight that it is not noticeable, and with flattened outer arch, the weight of the 20 body is thrown on the outer side of the sole of the shoe and particularly on the cushion of the foot under the small toe which results in the shoe running over. It is an object of my invention to overcome this disadvantage.

The invention consists in the details of construction and in the combination and arrangement of the several parts of my improved foot supporter whereby certain important advantages are attained and the device is rendered simpler, less expensive and otherwise more convenient and advantageous for use, all as will be hereinafter more fully set forth.

35 The novel features of the invention will be carefully defined in the appended claim.

In order that my invention may be the better understood, I will now proceed to describe the same with reference to the accompanying drawings, wherein—

Figure 1 is a view in top plan illustrating a supporter constructed in accordance with an embodiment of my invention, the outline of the sole of a shoe being indicated by dotted lines; Fig. 2 is a sectional view taken substantially on the line 2—2 of Fig. 1; and Fig. 3 is a sectional view taken substantially on the line 3—3 of Fig. 1.

As disclosed in the accompanying drawings, my improved supporter comprises the body B preferably formed of leather and having its rear extremity of such a contour as to snugly fit within the heel portion of the shoe with said body gradually reduced 55 in thickness transversely so that the weight

of the body will be properly distributed and the forward portion 2 of the body has one side provided with the extended portion 3 at the tickier side of the supporter adapted to extend forwardly of the shoe and terminate at that portion of the shoe which underlies the part of the ball of the foot immediately adjacent the small toe, and it is to be observed that the transverse curvature of the forward end of the body is on substantially a sigmoidal curve so that the cushion of the large toe joint is permitted to rest directly on the sole of the shoe proper. It is also to be noted that the free end portion of the extended portion 3 is gradually reduced longitudinally in thickness so that no discomfort will be afforded to the wearer of the shoe. In practice, it has been found that my improved supporter serves to rest the cushion of the small toe joint and in this way throws the weight to the inside of the foot thereby relieving the pressure on the ball of the foot under the small toe joint thus distributing the weight more to the large toe joint and thereby assuring a more even wear upon the shoe.

From the foregoing description, it is thought to be obvious that a foot supporter constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

In combination with a shoe, a supporter adapted to be inserted within the shoe and of a length less than the length of the shoe, the heel portion of the supporter fitting snugly within the heel portion of the shoe, said supporter being provided at its forward end with an extension, the forward edge of which is substantially sigmoidal in form, the forward edge of the supporter terminating rearwardly of the toe of the shoe so that the toes of the foot applied within the shoe may contact directly with the shoe, said sup-

110

porter being gradually reduced in thickness transversely with the thicker edge disposed along the longer side of the extension, the forward margin of the extension being reduced in thickness longitudinally of the support.

In testimony whereof I hereunto affix my signature in the presence of two witnesses.

CARL J. WATROUS.

Witnesses:

EDNA RHODES,
MARCUS B. CHASE.
